(57)

CLAIM

The ornamental design for a single device electrical junction box, as shown and described.

DESCRIPTION

FIG. 1 is a front, top perspective view of a single device electrical junction box;

FIG. 2 is a first end perspective view thereof;

FIG. 3 is a second end perspective view thereof; and,

FIG. 4 is a top perspective view thereof.

The broken lines in the drawings depict portions of the single device electrical junction box that form no part of the claimed design.
